CLAIM

An ornamental design for an electrical connector housing, as shown and described.

DESCRIPTION

FIG. 1 is a top, rear, and side perspective view of an electrical connector housing showing our new design; FIG. 2 is a perspective view of the electrical connector housing showing the bottom, front, and the side that is shown in FIG. 1;

FIG. 3 is a perspective view of the electrical connector housing showing the top, front, and opposite side;

FIG. 4 is a perspective view of the electrical connector housing showing the top, rear, and the side that is shown in FIG. 3;

FIG. 5 is a top view of the electrical connector housing;

FIG. 6 is a bottom view of the electrical connector housing;

FIG. 7 is a front view of the electrical connector housing;

FIG. 8 is a side view of the electrical connector housing;

FIG. 9 is an opposite side view of the electrical connector housing; and,

FIG. 10 is a rear view of the electrical connector housing.
